SLUB CATCHER

Peter B. Lewis, Aberdeen, N. C., assignor to Robbins Cloth Mills, Inc., Robbins, N. C., a corporation of North Carolina

Application June 15, 1949, Serial No. 99,177

7 Claims. (Cl. 28—64)

1

This invention relates to an improved slub catcher of a type such as is commonly used on cone winding machines and the like.

It is an object of this invention to provide a slub catcher having conventional yarn guiding means associated therewith and on which an anvil or thread plate is provided over which the yarn passes. A leaf spring blade extends downwardly from an arm disposed above the anvil, and is so mounted that it is drawn into engagement with the top surface of the anvil, upon slubs or other projections on the yarn engaging the blade as the yarn passes between the lower edge of the blade and the upper surface of the anvil, to thus grip the yarn between the lower edge of the blade and the anvil and to cause the yarn to break and to thereby activate the stop motion mechanism of the winder, not shown, and prevent a slub from being wound onto the package with the rest of the yarn.

It is another object of this invention to provide an apparatus of the type described with a resilient blade and a cam member engaging the blade, on the side thereof nearest the direction from which the yarn is being drawn to thus hold the lower end of the blade a predetermined distance from the upper surface of the anvil. The cam is adjustable so as to provide for various sizes or counts of yarn and to permit predetermined sizes of slubs to pass beneath the same, if so desired, while others of the slubs would engage the blade, thus moving the blade into engagement with the anvil to sever the yarn. The blade at its upper end has a centrally located slot to increase its flexibility but without allowing the blade to twist on its longitudinal axis.

Some of the objects of the invention having been stated, other objects will appear as the description proceeds, when taken in connection with the accompanying drawings, in which—

Figure 1 is a top plan view of a slub catcher embodying my improved structure;

Figure 2 is a longitudinal vertical sectional view through the slub catcher taken substantially along the line 2—2 in Figure 1;

Figure 3 is a schematic showing of the right-hand central portion of Figure 2 and showing the manner in which the spring blade catches a slub in the yarn passing between the lower edge of the same and the anvil;

Figure 4 is a vertical sectional view showing the blade and the mounting therefor in elevation and is taken along the line 4—4 in Figure 1;

Figure 5 is a side elevation of the slub catcher looking substantially along the line 5—5 in Figure 4;

2

Figure 6 is a view similar to Figure 3, but showing the cam bar for holding the blade a predetermined distance from the anvil in a different adjusted position.

Referring more specifically to the drawings, the slub catcher is herein shown as a bracket or frame broadly designated at 10 which may be of cast metal and which comprises a pair of substantially parallel longitudinally extending side portions 11 and 12, both of which are curved upwardly at their left-hand ends in Figures 1 and 2, and at their right-hand ends in Figure 5. The side portion 11 then has an inwardly curved portion 13 integral therewith which is integral at its inner end with a downwardly and inwardly projecting portion 14. The side portion 12 also has a downwardly and inwardly projecting portion 15 which converges relative to the portion 14 and is joined to the same and thus forms a slot 17 between the portions 14 and 15 for inserting a strand of yarn Y in a thread guide or poteye 20, preferably of porcelain material, and upwardly through which the yarn Y passes from a suitable bobbin, not shown.

The yarn then moves forwardly from the poteye 20 in Figures 1 and 2 and passes between conventional cup-shaped yarn tension members 22 and 23 loosely mounted on a post 24, the lower end of which is threadably imbedded in a spider-like central portion 25 of the slub catcher frame 10. A conventional shock absorbing disk 27 is supported in the upper cup-shaped tension member 23 and, in turn, supports a conventional weight disk 28, both the members 27 and 28 being loosely mounted on the post 24.

The side portion 12 has a resilient arm portion 30 integral therewith which extends from near the front end of the side portion 12 in Figures 1 and 2 to the rear of the frame 10 and has an upper gate portion 32 integral therewith which may be adjustably spaced apart from a lower gate portion 33, integral with and bridging the side portions 11 and 12, by an adjustment screw 35. The side portion 12 in Figure 2 also has a downwardly extending bearing portion 37 integral therewith which is provided with a bore 40 for reception of a conventional bracket supporting bar, not shown, of a spooler or winding machine, such as a Foster winder.

The structure thus far described embodies only the conventional parts of a slub catcher, and it is with these parts that the present invention is adapted to be associated.

The side portion 12 of most slub catchers usually has an upwardly projecting portion 41 which supports a conventional laterally extend-

ing thread guiding rod 42. In the present instance, the upwardly projecting portion 41 also has the restricted end of a suitable anvil 44 fixedly secured therein as by a set screw 45 (Figure 5), this anvil 44 having a flat upper surface 46 over which the yarn Y is adapted to pass. The yarn Y is then threaded beneath the rod 42 and between the upper and lower gate portions 32 and 33 of the bracket 10 and passes therebetween in the direction indicated by the arrows in Figures 1, 2 and 3. The other end of the anvil 44, or the right-hand end thereof in Figure 4, is supported on the longitudinally extending side portion 11 of the bracket 10.

The resilient arm portion 30 of the bracket 10 has an upwardly projecting post 47 integral therewith which is disposed closely adjacent the upper gate portion 32 and which is provided with a tongue or ridge 50 which is adapted to slidably receive a mating grooved block member 51 mounted for vertical adjustment against the upwardly projecting post 47. The block 51 has a vertical adjustment slot 52 therein which is slidably penetrated by a screw 53 for securing the block 51 in adjusted position against the left-hand face of the upwardly projecting post 47 in Figure 2.

To assist in adjusting the block 51 relative to the portion 47, the screw 53 is tightened snugly against the outer surface of the block 51, with the upper end of the block 51 being disposed at a slightly higher elevation relative to the post 47 than is desired, and then a screw 55, threadably imbedded in the upper end of the post 47, is tightened against the upper end of the member 51 to thus move the same downwardly until the lower edge of a spring steel blade 65, to be later described, has moved to a predetermined distance from the upper surface 46 of the anvil 44. The screw 53 is then driven home to hold the block 51 in this adjusted position.

The block 51 also has a vertical slot 56 therein which extends downwardly from the upper end thereof. The blade 65 also has a transverse slot 57 therein which is of sufficient depth to permit a portion 60, defined by the slots 56 and 57, to be moved inwardly toward the block 51, by a screw 61, which slidably penetrates the portion 60 and is threadably imbedded in the block 51. The reason for moving the portion 60 inwardly is to clamp a blade supporting pivot pin 62 in the block 51, the blade supporting arm 62 slidably penetrating said block 51, and having a screw driver slot 63 therein for adjusting the blade supporting arm 62 on its axis and to thereby increase or decrease the tension in the spring steel blade 65 which is carried by the blade supporting arm 62.

The blade supporting arm 62 is positioned rearwardly of the vertical plane of the longitudinal axis of the anvil and the blade 65 extends downwardly and forwardly at a slight angle, say 8 degrees, from the arm 62 and has a centrally located vertically extending slot 67 therein which is provided to increase the normal sensitivity of the spring steel blade 65. The slot 67 preferably extends from the upper edge of the blade and terminates about midway of the blade 65. The blade 65 is clampingly secured to the arm 62 by a bar 70 which is secured to the blade supporting arm 62 as by screws 71 (Figures 3 and 4).

It has already been stated how the blade 65 is vertically adjustable so as to position the lower edge of the same a predetermined distance above

the upper surface 46 of the anvil 44 according to the size or count of yarn adapted to be passed therebetween. By forming the slot 67 in the center of the blade 65 the desired strength of the blade is determined, yet the blade, on account of having its side edge portions intact, prevents twisting of the blade along its longitudinal axis in the event a slab is caught by the blade 65 near one of its lower corners.

Now, to further insure that the distance between the lower edge of the blade 65 and the upper surface 46 of the anvil 44 may be maintained and to provide for varying the amount of tension in the blade 65, which tension must be overcome by a slab portion Y-1 or an elongated thick place Y-2 in the yarn Y, a horizontally disposed cam bar 75, having a cam face 76 on its side nearest the blade 65, is positioned to extend across the front surface of the spring blade 65.

This cam member 75 has a restricted end portion 77 which slidably penetrates the resilient arm portion 30 of the bracket 10 and has a nut 80 threadably mounted on its outer end to thus lock the cam member 75 in an adjusted position. The other end of the cam member 75 has a screw driver slot 81 therein and by inserting a screw driver in the slot 81 and loosening the nut 80 slightly on the restricted portion 77, the cam member 75 may be adjusted, as to angularity of its face 76, to thus insure that the lower end of the blade 65 will normally remain in a predetermined position relative to the longitudinal axis of the anvil 44. The cam bar 75 will also permit the tension in the spring blade 65 to be increased by partially rotating the blade supporting arm 62 in a clockwise direction in Figure 2. Thus, through cooperating adjustment of the vertically adjustable block 51, the blade supporting bar 62 and the cam bar 75, the lower edge of the blade 65 may be adjusted to a predetermined position relative to the upper surface 46 of the anvil 44 and a predetermined amount of tension in the spring steel blade 65 may be maintained at its lower edge, which must be overcome by slab portions Y-1 or Y-2 or other projections on the yarn Y, moving against the blade 65 as shown in Figure 3.

Obviously, upon the slab portions Y-1 or Y-2 engaging the lower edge of the blade 65, the blade will be biased to the right as shown in Figure 3, and since the blade is positioned slightly off center in a vertical plane relative to the axis of the anvil 44, the lower edge of the blade will engage the top surface 46 of the anvil 44 thus clamping the yarn therebetween and causing the yarn to break between its clamping point and the package, not shown, on which the yarn is being wound.

There have been other attempts made to provide for the use of a spring steel or flexible blade for severing or breaking the yarn upon the blade being contacted by a slab or projection in the yarn; however none of these has proved successful or efficient, due to the fact that parts have been positioned rearwardly or away from the direction of travel of the yarn relative to the blade, and lint from the yarn would collect between the blade and these other parts, thus decreasing the radius of action of the free end of the blade and resulting in inefficient operation of the slab catching feature, and, in some instances, rendering it completely inoperative. This detriment has been overcome in the present invention by the inclusion of the cam bar 75 mounted in a

position with respect to the blade 65 toward the direction from which the yarn is travelling as it passes beneath the lower edge of the blade. It is seen that it would then be impossible for lint to collect rearwardly of the blade, inasmuch as there are no obstructions whatsoever on which lint may collect adjacent the rear surface of the blade.

In the drawings and specification there has been set forth a preferred embodiment of the invention, and although specific terms are employed, they are used in a generic and descriptive sense only, and not for purposes of limitation, the scope of the invention being defined in the claims.

I claim:

1. A slub catcher for textile yarns comprising a bracket adapted to be mounted in a substantially horizontal plane and having a resilient arm at one side thereof disposed in a substantially parallel relation to the bracket, an anvil extending laterally across said bracket and having a flat upper surface across which the yarn is adapted to pass, an upwardly projecting post integral with said arm, a vertically adjustable block mounted on the upwardly projecting post, an arm extending laterally from the vertically adjustable block and being disposed slightly offset from a vertical plane passing through the anvil, a cam bar extending in spaced parallel relation to the anvil and being disposed between the anvil and the bar extending from said block, a resilient blade extending from the bar and terminating in slightly spaced relation to the upper surface of the anvil, the surface of the blade facing the source from which the yarn is moving being adapted to normally engage the cam member whereby, upon a slub portion in the yarn engaging said blade as the yarn passes between the lower edge of the blade and the anvil, the lower edge of the blade will be drawn away from the cam bar and into engagement with the anvil to clamp the yarn therebetween and to cause it to break under tension.

2. A slub catcher for yarn traveling therethrough comprising a bracket adapted to be mounted in a substantially horizontal position and having an upwardly projecting post integral therewith, a blade supporting arm extending laterally from said upwardly extending post and an inherently resilient blade having its upper end secured to and depending from said blade supporting arm, the blade having a longitudinally extending slot in its upper end to increase the flexibility of the blade, a laterally extending anvil disposed closely adjacent the lower end of said blade and over which the yarn is adapted to pass, means for adjusting said blade as to angularity relative to the vertical, so that a projection in the yarn, upon attempting to pass beneath the lower edge of said blade, will engage the blade to urge the same into engagement with the upper surface of the anvil thus clamping the yarn therebetween, and causing the yarn to break, and adjustable stop means for arresting movement of the lower end of the blade in a direction towards the source of the yarn.

3. A slub catcher for yarn traveling therethrough comprising a bracket adapted to be mounted in a substantially horizontal position and having an upwardly projecting post integral therewith, a blade supporting arm extending laterally from said upwardly extending post and a leaf spring blade having its upper end secured to and depending from said blade supporting arm,

the blade being rectangular in shape and having a longitudinally extending and centrally disposed slot extending from its upper end to a point removed from the lower edge of the blade, a laterally extending anvil disposed closely adjacent the lower end of said blade and over which the yarn is adapted to pass, means for adjusting said blade as to angularity relative to the vertical, so that a projection in the yarn, upon attempting to pass beneath the lower edge of said blade, will engage the blade to urge the same into engagement with the upper surface of the anvil thus clamping the yarn therebetween, and causing the yarn to break, and adjustable stop means for arresting movement of the lower end of the blade in a direction towards the source of the yarn.

4. In a yarn guiding apparatus having a frame adapted to be mounted in a substantially horizontal plane and through which yarn is adapted to be passed, slub catching means therefor comprising an anvil mounted in the frame and over which the yarn is adapted to pass, a leaf spring blade, means on the bracket for mounting the upper end of the blade with its lower end in predetermined spaced relation to the upper surface of said anvil, the blade having a longitudinally extending slot in its upper end to increase the flexibility of the blade, means adjustable towards and away from the blade and normally engaging the surface of said blade nearest the source of yarn to limit movement of the lower edge of the blade towards the source of yarn whereby, upon a projection in the yarn attempting to pass between the lower edge of said blade and the upper surface of the anvil, the blade having a longitudinally extending slot in its upper end to increase the flexibility of the blade, means adjustable towards and away from the blade and normally engaging the surface of said blade nearest the source of yarn to limit movement of the lower edge of the blade towards the source of yarn whereby, upon a projection in the yarn attempting to pass between the lower edge of said blade and the upper surface of the anvil, the projection will move the blade away from the said means normally engaging the surface of the blade to thus clamp the yarn between the lower edge of the blade and the anvil and whereupon further attempts to pull the yarn past the lower edge of the blade will cause the yarn to break.

5. In a yarn guiding apparatus having a frame adapted to be mounted in a substantially horizontal plane and through which yarn is adapted to be passed, slub catching means therefor comprising an anvil mounted in the frame and over which the yarn is adapted to pass, a leaf spring blade, an oscillable pivot pin on the bracket for mounting the upper end of the leaf spring blade with its lower end in predetermined spaced relation to the upper surface of said anvil, the blade being rectangular in shape and having a longitudinally extending and centrally disposed slot extending from its upper end to a point removed from the lower edge of the blade, means adjustable towards and away from the blade normally engaging the surface of said blade nearest the source of yarn to assist in normally holding the lower edge of the blade in fixed relation to the anvil means for securing the oscillable pivot pin against oscillation and to hold it against the means normally engaging its surface next to the source of yarn whereby, upon a projection in the yarn attempting to pass between the lower edge of said blade and the upper surface of the anvil, the projection will move the blade away from the said means normally engaging the surface of the blade to thus clamp the yarn between the lower edge of the blade and the anvil and whereupon further attempts to pull the yarn past the lower edge of the blade will cause the yarn to break.

6. A slub catcher for textile yarns comprising a bracket adapted to be mounted in a substantially horizontal plane and having a resilient arm

at one side thereof disposed in substantially parallel relation to the bracket, an anvil extending laterally across said bracket and having a flat upper surface across which the yarn is adapted to pass, an upwardly projecting post integral with said arm, a vertically adjustable block mounted on the upwardly projecting post, an arm extending laterally from the vertically adjustable block and being disposed slightly off-set from a vertical plane passing through the anvil, a cam bar extending in spaced parallel relation to the anvil and being disposed between the anvil and the bar extending from said block, a resilient blade extending from the bar and terminating in slightly spaced relation to the upper surface of the anvil, the blade having a longitudinally extending slot in its upper end to increase the flexibility of the blade, the surface of the blade facing the source from which the yarn is moving being adapted to normally engage the cam member whereby, upon a slab portion in the yarn engaging said blade as the yarn passes between the lower edge of the blade and the anvil, the lower edge of the blade will be drawn away from the cam bar and into engagement with the anvil to clamp the yarn therebetween and to cause it to break under tension.

7. A slab catcher for textile yarns comprising a bracket adapted to be mounted in a substantially horizontal plane and having a resilient arm at one side thereof disposed in substantially parallel relation to the bracket, an anvil extending laterally across said bracket and having a flat upper surface across which the yarn is adapted to pass, an upwardly projecting post integral with

5 10 15 20 25 30 35

said arm, a vertically adjustable block mounted on the upwardly projecting post, an arm extending laterally from the vertically adjustable block and being disposed slightly off-set from a vertical plane passing through the anvil, a cam bar extending in spaced parallel relation to the anvil and being disposed between the anvil and the bar extending from said block, a resilient blade extending from the bar and terminating in slightly spaced relation to the upper surface of the anvil, the blade being rectangular in shape and having a longitudinally extending and centrally disposed slot extending from its upper end to a point removed from the lower edge of the blade, the surface of the blade facing the source from which the yarn is moving being adapted to normally engage the cam member whereby, upon a slab portion in the yarn engaging said blade as the yarn passes between the lower edge of the blade and the anvil, the lower edge of the blade will be drawn away from the cam bar and into engagement with the anvil to clamp the yarn therebetween and to cause it to break under tension.
